TREE ORNAMENT

Roger L. Martin, San Jose, Calif., assignor to Container Corporation of America, Chicago, Ill.

Filed Mar. 8, 1974, Ser. No. 449,360

Term of patent 14 years

Int. Cl. D11—02

U.S. Cl. D29—1 A

FIG. 2

FIG. 1

FIG. 3

FIG. 1 is a top plan view of a tree ornament showing my new design;

FIG. 2 is an edge elevational view thereof taken substantially along the line 2—2 of FIG. 1; and

FIG. 3 is a side elevational view thereof taken substantially along the line 3—3 of FIG. 1.

I claim:

The ornamental design for a tree ornament, as shown.
